TOY AEROPLANE PROPELLER MOUNTING

Nevilles E. Walker, Portland, Oreg.

Application September 4, 1936, Serial No. 99,364

19 Claims. (Cl. 46—78)

My invention relates to toy aeroplanes and has for a specific object the provision of simple and inexpensive means for mounting the propeller and the landing gear, said parts being arranged to withstand substantial shock without destructive distortion.

Further and more specific methods of my invention are to provide a propeller mounting which is:

1. Capable of accommodating a propeller of uniform thickness without requiring said propeller to be perforated or otherwise weakened to secure a hub or journal thereto;

2. Which is resiliently mounted in the fuselage so that the propeller can be easily twisted out of its operating plane to prevent breakage when said toy aeroplane strikes the ground nose first, which mounting firmly holds the propeller and the hub to prevent relative rotation thereof, and which structure is adapted to permit the propeller to be mounted on the fuselage without unshipping or removing said propeller in packaging said toy aeroplane, said features being present in a mounting which automatically and resiliently arranges the propeller at its proper flying angle;

3. One which imposes increased resistance to the rotation of the propeller under the influence of a twisted band motor when said band motor is twisted to maximum distortion, said resistance retarding the effective speed of rotation of said propeller, said mounting progressively decreasing the resistance as said band motor untwists thereby permitting freer rotation of said propeller and securing a more uniform overall flying speed when used with an uncoiling rubber band which gives varying torque to the propeller;

4. A mounting which permits the use of simple, light and efficient anti-friction bearings for the propeller involving negligible expense and efficient action;

5. A mounting which provides a convenient detachable support for the landing gear and its support which landing gear engages said mounting and tends to increase the engagement between said mounting and the fuselage of said toy aeroplane; and

6. A mounting which permits the use of a relatively small quantity of metal and permits the use on the remainder of said toy aeroplane of light balsa wood and thin propellers to increase the flying range and flying ability of said toy aeroplane.

Further and other objects and advantages of my invention are hereinafter described with reference to the accompanying drawing in which:

Fig. 1 is a perspective view of a toy aeroplane embodying my invention;

Fig. 2 is a fragmentary plan view of the propeller mounting with portions of the fuselage and propeller shown joined thereto;

Fig. 3 is an elevation of the forward end of the fuselage, the propeller and its mounting, illustrating how the propeller can be tipped angularly out of its normal flying plane in said mounting thru the resilient manner in which said propeller is seated in said mounting;

Fig. 4 is a side elevation of said mounting, a portion being shown broken away to disclose details of construction;

Fig. 5 is a longitudinal section thru said mounting and the associated parts taken substantially on the line 5—5 in Fig. 4;

Fig. 6 is an enlarged sectional view thru the propeller hub, the anti-friction bearings and the forward end of the propeller mounting, and

Fig. 7 is a sectional view taken on the line 7—7 in Fig. 6 thru the anti-friction bearings and illustrates the construction thereof.

A toy aeroplane embodying my invention comprises a fuselage *a* which may be in the form of an elongated rectangular wooden section. Extending thru a slot *a'* formed in said fuselage is a single wing structure *b*. The tail structure comprises two members *c* and *d*, secured to the rear end of said fuselage, the member *c* extends vertically in a slot *a2* formed at the rearward edge of said fuselage and a horizontal tail member *d* is secured to the under side of said fuselage by the rubber band or similar element *e*.

At the forward end of the fuselage a nose piece *f* is provided which constitutes the principal portion of the propeller mounting. A tubular hub *g* is journaled in the depending forward end of the nose piece *f* being journaled in a hole *h* formed in said forward end. Said nose piece is formed of an integral section of metal U-shaped in section. The principal web *f2* overlies the tapered forward end *a3* of the fuselage, this being illustrated in Fig. 4.

Laterally projecting flanges *f3* and *f4* extend downwardly as is indicated most clearly in Figs. 1 and 3, and engage the sides of said tapered forward end *a3*. Underlying said forward end are two inwardly bent lips *f5* and *f6* which encircle said underside and hold the nose piece in place. Extending rearwardly from the flanges *f3* and *f4* are spring-like clamps *f7* and *f8*, as is indicated in Figs. 2 and 5. Said clamps define two laterally aligned grooves *i*—*i'* for accommodating a bifurcated resilient landing gear sup-

port *j*. Said landing gear support *j* preferably is made of a single piece of wire, such for example as piano wire, and at the middle an inverted U-shaped structure *j'* is formed. Said U-shaped structure overlies the web *j2* of the nose piece and engages and grips the clamping elements *j1* and *j8* between them. Said U-shaped structure seats in the grooves *i-i'* and thus is prevented from shifting laterally on said nose piece. At the lower end, wheels *k-k'* are provided which are carried by laterally offset projections *j2* at the ends of the wire forming the landing support gear *j*.

The forward end of said nose piece spreads and broadens out into a mushroom head *j9* in which the hole *h* is formed. Said mushroom-shaped head provides adequate bearing for maintaining the hub *g* in its proper angular position with respect to the longitudinal dimension of the fuselage to provide correct flying angle for said aeroplane. The twisted rubber band rotor *e* is secured at its rearward end upon a hook *l* depending downwardly from the fuselage. Said rubber band motor preferably is arranged in endless form and the rearward loop extends about said hook and the forward end passes thru the bore of the tubular hub *j* and is looped about the middle of the propeller *m*. The propeller is made of relatively thin strong material, but of uniform thickness. This permits the propeller to be stamped out of sheets of material and twisted to proper shape rather than requiring said propeller to be shaped out of a relatively large block of wood with the attendant waste and manufacturing expense to secure a thick hub.

Said tubular hub is provided with slots *g'* of sufficient width to accommodate the propeller. Said slots are adapted to fit snugly against the sides of the propeller so as to prevent substantial play. Said slots are arranged relatively angularly to each other and to the axial dimension of the tubular hub so that the propeller is not required to have a flat central section to seat in said slots. Said slots extend from the forward edge of the propeller rearwardly a sufficient distance to accommodate the width of the central part of said propeller. Extending rearwardly of said propeller is a laterally formed shoulder *g2* formed in the hub *g*. Said shoulder preferably is formed by crimping the material of which the tubular hub is formed to define a laterally extending exterior flange of double the thickness of the walls of said hub. Said flange is of sufficiently great diameter to provide a solid shoulder for alining the hub correctly with respect to the nose piece.

I preferably provide an anti-friction bearing *n* between said shoulder *g2* and the forward mushroom shaped head *j9* of the nosepiece. Said anti-friction bearing is preferably constructed of two opposed cups *n'* and *n2*. The cup *n'* is of slightly larger diameter than the cup *n2* and thus the cup *n2* nests within the cup *n'*, as is shown in Fig. 6. Ball bearings *n3* are housed within said cups in a flat race *n4*. Said race *n4* is preferably crimped within the rim of the cup *n2* to rotate therewith. When said anti-friction bearing is in place, the rearward end *g3* of the tubular hub is flared outwardly so as to prevent said hub from being retracted from the nosepiece. This is shown most clearly in Figs. 5 and 6.

The rubber band motor *e* extends thru the bore of said hub and is permitted free movement in said bore inasmuch as the diameter of said bore is substantially greater than the width of the

rubber band as is indicated in Fig. 5. As has previously been stated, said rubber band is preferably arranged in endless form and extends about the central portion of said propeller. Said propeller is provided with a lateral projection *m'* at its middle which is substantially of the same width as the diameter of the tubular hub so as to fit into said bore and to hold said propeller against lateral shifting in the slot *g'* when said propeller is resiliently held in said slots by the action of the rubber band motor.

When the rubber band motor is arranged about said propeller the latter is permitted to be tipped easily as is shown in Fig. 3, if the rubber band is not twisted severely to shorten its overall length. This permits the propeller to be swung out of its normal position to permit easy packaging of the said toy aeroplane without removing said propeller. The propeller is prevented from shifting laterally by said central offset portion *m'*. Said propeller structure also permits the propeller to be moved angularly to prevent breakage of said propeller if said toy aeroplane strikes a solid object at the end of its flight, or ends nose down on the ground or otherwise strikes some solid object.

One of the difficulties in using a rubber band motor is that its distortion when twisted tends to provide greater torque when it is twisted to its maximum degree and a decreasing torque as said rubber band becomes untwisted. This tends to cause the propeller to be rotated at a higher speed at the commencement of flight and a correspondingly lower speed as the untwisting continues. By securing the propeller directly to the rubber band so that it tends to become seated more tightly as the overall length of the rubber band diminishes when twisted, a corresponding increase in resistance to rotation is secured. Thus, when the rubber band is twisted to its maximum degree it imposes a correspondingly increased friction to prevent rotation of said propeller. As said band becomes untwisted said friction decreases somewhat in proportion to the force exerted by the partly untwisted rubber band. This structure causes the speed of the propeller under the influence of said rubber band to become more uniform over a sustained flight and increases the flying ability of said toy aeroplane. Anti-friction bearings are interposed to minimize said friction and do not disturb this relationship but do prevent said friction from becoming too great to prevent the propeller from rotating freely.

The wings and tail structure and fuselage of said toy aeroplane are preferably constructed of balsa wood and the nose piece is preferably constructed of relatively thin stamped sheet metal, such for example, as thin copper or aluminum. The tubular hub bearings are also constructed of relatively light materials of thin sections and the propeller may be constructed of hard wood or ply wood. The propeller being of uniform thickness may be easily and inexpensively stamped from a sheet of uniform thickness and distorted to proper pitch.

I claim:

1. In a toy aeroplane comprising a fuselage, wing and tail structures, a propeller blade rotatably mounted at the forward end of said fuselage and a resilient band motor for rotating said propeller, a mounting for said propeller comprising a nose piece secured to said fuselage having a seat formed in its forward end a slotted hub journaled therein, said propeller being of uniform

thickness releasably engaging said hub at its middle.

2. In a toy aeroplane comprising a fuselage, wing and tail structures, a propeller blade rotatably mounted at the forward end of said fuselage and a resilient band motor for rotating said propeller, a mounting for said propeller including a hub rotatably secured to said fuselage having a slotted seat formed in its forward end, said propeller being of uniform thickness releasably engaging said seat at its middle, said band motor extending longitudinally of said hub about said propeller, and resiliently holding said propeller in its seat.

15 3. In a toy aeroplane comprising a fuselage, wing and tail structures, a propeller blade rotatably mounted at the forward end of said fuselage and a resilient band motor for rotating said propeller, a mounting for said propeller including a tubular hub rotatably secured to said fuselage having a slotted seat formed in its forward end, said propeller being of uniform thickness releasably engaging said seat at its middle, said band motor extending thru the bore of said tubular hub, about said propeller and resiliently holding said propeller in its seat.

20 4. In a toy aeroplane comprising a fuselage, wing and tail structures, a propeller blade rotatably mounted at the forward end of said fuselage and a resilient band motor for rotating said propeller, a mounting for said propeller including a separable hub rotatably secured to said fuselage having a seat formed in its forward end, said propeller being of uniform thickness engaging said seat at its middle, said band motor extending longitudinally of said hub, about said propeller, and resiliently holding said propeller in its seat.

25 5. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a journal formed therein, a member journaled in said nose piece, said propeller mounted in a seat formed in said member, said band motor extending longitudinally of said member and engaging the propeller at its middle, resiliently holding said propeller in said seat formed in said member.

30 6. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a journal formed therein, a member journaled in said nose piece, said propeller mounted in a seat formed in said member, said band motor extending longitudinally of said member and engaging the propeller at its middle, resiliently holding said propeller in said seat formed in said member, a lateral shoulder on said member operatively restraining the lateral displacement of said member with respect to said nose piece.

35 7. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a journal formed therein, a member journaled in said nose piece, said propeller mounted in a seat formed in

said member, said band motor extending longitudinally of said member and engaging the propeller at its middle, resiliently holding said propeller in said seat formed in said member, a lateral shoulder on said member operatively restraining the lateral displacement of said member with respect to said nose piece and a bearing interposed between said shoulder and said nose piece.

40 8. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a journal formed therein, a member journaled in said nose piece, said propeller mounted in a seat formed in said member, said band motor extending longitudinally of said member and engaging the propeller at its middle, resiliently holding said propeller in said seat formed in said member, a lateral shoulder on said member operatively restraining the lateral displacement of said member with respect to said nose piece, and an anti-friction bearing interposed between said shoulder and said nose piece.

45 9. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a journal formed therein, a member journaled in said nose piece, said propeller mounted in a seat formed in said member, said band motor extending longitudinally of said member and engaging the propeller at its middle, resiliently holding said propeller in said seat formed in said member, a lateral shoulder on said member operatively restraining the lateral displacement of said member with respect to said nose piece, and an anti-friction bearing interposed between said shoulder and said nose piece, said anti-friction bearing comprising two opposed cups held in operative relation by an enlargement of said member.

50 10. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a journal formed therein, a slotted tubular member journaled in said nose piece, said propeller mounted in said slotted member, said band motor extending thru said tubular member and engaging the propeller at its middle, resiliently holding said propeller in said slotted member.

55 11. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a mushroom-shaped depending forward end and a journal formed therein, a slotted tubular member journaled in said nose piece, said propeller mounted in said slotted member, said band motor extending thru said tubular member and engaging the propeller at its middle, resiliently holding said propeller in said slotted member, a lateral shoulder on said tubular member operatively re-

- straining the lateral displacement of said member with respect to said nose piece.
12. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a depending forward end and a journal formed therein extending below said fuselage, a slotted tubular member journalled in said nose piece, said propeller mounted in said slotted member, said band motor underlying said fuselage and extending thru said tubular member and engaging the propeller at its middle, resiliently holding said propeller in said slotted member, a lateral shoulder on said tubular member operatively restraining the lateral displacement of said member with respect to said nose piece.
13. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece being of inverted U-shaped section and provided with a journal formed therein, a member journalled in said nose piece, said propeller mounted in a seat formed in said member.
14. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a depending forward end and a journal formed therein extending below said fuselage, a member journalled in said nose piece, said propeller mounted in a seat formed in said member, said band motor underlying said fuselage and extending longitudinally of said member and engaging the propeller at its middle, resiliently holding said propeller in said seat formed in said member.
15. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, said nose piece provided with a mushroom-shaped depending forward end and a journal formed therein extending below said fuselage, a member journalled in said nose piece, said propeller mounted in a seat formed in said member, said band motor underlying said fuselage and extending longitudinally of said member and engaging the propeller at its middle, resiliently holding said propeller in said seat formed in said member.
16. In a toy aeroplane comprising a fuselage, wing and tail structures, a propeller blade rotatably mounted at the forward end of said fuselage and a resilient band motor for rotating said propeller, a nose piece clamped to the forward end of said fuselage constituting a mounting for said propeller, two opposed clamping members on said nose piece gripping said forward end between them.
17. In a toy aeroplane comprising a fuselage, wing and tail structures, a propeller blade rotatably mounted at the forward end of said fuselage and a resilient band motor for rotating said propeller, a nose piece secured to the forward end of said fuselage constituting a mounting for said propeller, laterally alined grooves formed in said nose piece, a resilient bifurcated member constituting wheel supports, said member provided at its middle with a closely bent U-shaped structure straddling said nose piece and seated in said grooves.
18. In a toy aeroplane comprising a fuselage, wing and tail structures, a propeller blade rotatably mounted at the forward end of said fuselage and a resilient band motor for rotating said propeller, a nose piece clamped to the forward end of said fuselage constituting a mounting for said propeller, two opposed clamping members on said nose piece gripping said forward end between them, laterally alined grooves formed in said clamping members of said nose piece, a resilient bifurcated member constituting wheel supports, said member provided at its middle with a closely bent U-shaped structure straddling said clamping members of said nose piece and seated in said grooves.
19. In a toy aeroplane comprising a fuselage, wing and tail structures, a propeller blade rotatably mounted at the forward end of said fuselage and a resilient band motor for rotating said propeller, a nose piece clamped to the forward end of said fuselage constituting a mounting for said propeller, two opposed clamping members on said nose piece gripping said forward end between them, laterally alined grooves formed in said clamping members of said nose piece, a resilient bifurcated member constituting wheel supports, said member provided at its middle with a closely bent U-shaped structure straddling said clamping members of said nose piece and seated in said grooves and gripping said nose piece, tending to force the latter into tighter engagement with said fuselage.

NEVILLE S. WALKER.
